(57) **CLAIM**

The ornamental design for a cable tie, as shown and described.

DESCRIPTION

FIG. 1 is a front, top and left side perspective view of a cable tie showing our new design;

FIG. 2 is a front view thereof, the rear view being a mirror image of FIG. 2;

FIG. 3 is a top plan view thereof;

FIG. 4 is a bottom plan view thereof;

FIG. 5 is a right side view thereof;

FIG. 6 is a left side view thereof;

FIG. 7 is an enlarged view of the portion indicated by line 7-7 in FIG. 1;

FIG. 8 is an enlarged view of the portion indicated by line 8-8 in FIG. 2;

FIG. 9 is an enlarged view of the portion indicated by line 9-9 in FIG. 3;

FIG. 10 is an enlarged view of the portion indicated by line 10-10 in FIG. 4;

FIG. 11 is an enlarged right side view thereof;

FIG. 12 is an enlarged left side view thereof;

FIG. 13 is a cross-sectional view taken along line 13-13 in FIG. 9; and,

FIG. 14 is a cross-sectional view taken along line 14-14 in FIG. 9.

The broken lines in the drawings illustrate portions of the cable tie and form no part of the claimed design. The dot-dash-dot broken lines in the drawings define the bounds of the claim and form no part thereof.
